UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

PRINTING DEVICE.

Application filed November 2, 1925. Serial No. 66,227.

This invention relates to a printing device of the general type wherein raised printing members as embossed strips, are mounted on a rotary drum and coact with a suitable platen, especially when such a device is in the simple form adapted for office printing. An object of the invention is to provide simple means whereby a page wider than usual may be printed without requiring an increase in the width of the machine. Another object is to provide a very simple means for making a tabular form with columns accurately aligning.

In carrying out the invention, I provide a suitable rotary drum having a removable segment adapted to carry the printing lines, which segment is surmounted by an inking ribbon carried by spools mounted in the drum, and such device is adapted to coact with a rotary platen, as the drum is rotated. The device accordingly partakes of the character of a multigraph printing machine. Instead, however, of making the typeholding segment semi-cylindrical as in the multigraph, I extend it materially beyond a half cylinder, and I arrange undercut ribs extending arcuately about the surface of the segment instead of parallel with the axis, and instead of type between the ribs, I mount directly on the ribs, curved embossed printing strips.

I may divide the form into columns by means of flat strips of less height than the embossed characters which flat strips extend transversely of the embossed strips, and are provided on their ends with means for engaging overhanging ribs of the segment. By this means I am able to build up on the segment a tabular printing form accurately aligned.

The printing lines may extend for a considerable distance in excess of a semi-circle, enabling me to print a page which is materially wider than the length of the drum, moreover, by reason of portions of several lines coacting with the platen at the same time the depth of impression is substantially even irrespective of occasional short lines.

The features above referred to are herein-after more fully explained in connection with the embodiment illustrated in the drawings.

In the drawings, Fig. 1 is a side elevation of a printing device having my segment with arcuate ribs; Fig. 2 is a cross section same as

indicated by the line 2-2 on Fig. 1; Fig. 3 is a section on the reduced scale of the strip holding segment; Fig. 4 is a sectional perspective of a portion of said segment, the plane of the section being parallel with the axis; Figs. 5 and 6 are fragmentary cross-sections of the segment in planes transverse to the axis; Fig. 7 is a development of the segment, showing a tabular printing form mounted thereon; Fig. 8 is a longitudinal section through the segment intermediately broken away and showing the relation of the positioning strips; Fig. 9 is a perspective of one of the positioning strips.

As shown in Figs. 1 and 2, 10 indicates the frame of a printing machine, 11 the main shaft journaled therein, 12 a crank for rotating the shaft, 13 a pair of skeleton disks rigidly secured to the shaft and having connecting cross-rods 14. The crank is shown as driving a pinion 15 meshing with a gear 16 on one of the disks 13.

The segment is designated 20 and comprises a wall portion extending for more than a semi-circumference and provided on its exterior with dove-tailed or overhanging ribs 21 arcuately arranged parallel with each other, and on its interior with transverse webs 23. The webs 23 may conveniently be plates made separately from the arcuate wall and suitably secured against annular shoulders on the inner surface of that wall as shown in Fig. 3. Near its ends the inner surface of the cylindrical wall bears on the rotary disks 13, while the webs 23 may bear on the rods 14. The segment may be held in place by spring hooks 30 pivoted to the segment by means of a rod 31 extending across the webs and at its other end springing around the shaft 11 or a sleeve thereon, after the manner of Patent No. 1,122,728 issued December 29, 1914, to my assignee, The American Multigraph Company.

The end disks 13 of the skeleton drum are shown as carrying a pair of ribbon spools 40 from which an inking ribbon 41 extends about the printing form. Such form coacts with a rotary platen 45 suitably carried by the frame, and geared with the skeleton drum. The machine is accordingly adapted when the crank is rotated to print on paper fed between the drum and platen.

I prefer to make the arcuate overhanging ribs 21 integral with the wall of the segment, making them by milling flaring grooves 24

between them, the final cut of the milling machine being by an inclined thin cutting disk. The desired distance between the ribs allows sufficient space for this cutter. The 5 ribs have their outer surface truly cylindrical, then for a short distance they have edges at substantially right angles to the outer surface, and then the opposite sides of such rib converge by surfaces which are zones of 10 a cone, all as clearly shown in Fig. 4.

The printing members comprise embossed strips 50 having a single row of upwardly extending characters 51 thereon and having the edges 52 of the strips extending away 15 from the embossed surface and inclining inwardly toward each other. Such a strip may be made by any suitable machine, as for instance, the embossing machine forming the subject matter of my Patent No. 1,557,754 20 issued October 20, 1925, and when made respond to claim 205 of that patent.

The embossed strips when produced are preferably straight, but are made of comparatively soft material, as aluminum or 25 zinc, and when shoved onto the arcuate ribs 21 are correspondingly curved thereby to snugly embrace the ribs, as shown. To enable the strips to be conveniently inserted I prefer to chamfer or round off the ribs at 30 one end as indicated at 25 in Fig. 6. The other edge of the segment is provided with a suitable stop as for instance a bar 27 held to the segment by screws 28 and overlapping the ends of the ribs, thus causing the ends of 35 the strips which abut the bar to accurately align.

To enable the strips to be accurately positioned and held on the segment, so that the characters of one line may align with those 40 of another, which is very important in tabular numeral work, I provide intermediate locking strips illustrated at 60 in Figs. 4, 7, 8 and 9. These strips are thin ribbons of steel and each is provided at one end with 45 an inwardly inclined portion 61 adapted to lie parallel with the underface of a rib and at the other end with a portion 62 which extends inwardly at a less acute angle than the end portion 61 and then is curled slightly 50 outwardly at its extreme end 63. The length of the flat portion of such strips is equal to the width, parallel to the axis, of the face of several ribs plus the distance between these ribs. It results therefore that when 55 the end 61 is hooked over a rib, the end 62 may be sprung beneath the opposite edge of the distant rib, effectively holding the strip in place, as shown in Fig. 8. The angle of the end portion 62 while sufficient to hold 60 the strip in place, is chosen with reference to its being readily sprung into place, and this installing movement is facilitated by the outwardly curled extreme edge 63.

I find that it is entirely practicable to position the printing strips on the entire face

of the segment by means of strips 60 arranged in sets of two each, each strip of such set having its ends 61 hooked into the central channel 24^a in the segment and having their ends 62 sprung into engagement with 70 the outer surface of the extreme ribs 21.

The printing strips, when produced for mounting in any column on the segment, are properly of the same length, so that a succession of them may be abutted at their ends 75 by the same transverse holding strip 60. Thus, as shown in Fig. 7, the strips carrying the different names are continued by blank spaces in the embossing machine so that they all have a length as great as the longest line 80 produced; similarly the numeral strips have a length corresponding to the largest numbers of numerals to be used. It is in connection with numerals that the column alignment is most important. Accordingly if the maximum number of digits is six each strip 85 irrespective of the digits appearing thereon, will have a length corresponding to six digits and the numerals will be embossed on it in proper position. When these numeral 90 printing strips are placed on the segment and positioned by the transverse strips, the numerals of successive lines will accurately register in column.

It will be seen that by my system, I am 95 enabled to print a wide range with a comparatively small machine, and to print it with a very even impression, by reason of the pressure usually coming on a large number of lines instead of on one line at a time, 100 as in the usual multigraph. In addition to these advantages, I can lock the form very accurately in position and produce numeral tabular work in proper columns.

Having thus described my invention, I 105 claim:

1. In a printing device, the combination of a stiff type holding segment having continuous overhanging ribs extending arcuately thereon, and embossed printing strips 110 mounted on said ribs.

2. In a printing device, the combination of a segment having a rigid cylindrical wall with integral parallel continuous overhanging ribs extending arcuately about the wall 115 and arcuate embossed printing strips mounted on said ribs.

3. In a printing machine, the combination with a platen and rotary shaft, of a segment mounted about said shaft for rotation thereby in coaction with the platen, said segment having a cylindrical wall with external ribs extending arcuately parallel with each other, each rib having inwardly beveled side surfaces and having a base continuously connected with the segment, and embossed printing strips mounted on said ribs. 125

4. In a printing device, the combination with a rotary skeleton drum, of a segment mounted thereon and resting on the drum 130

- substantially in a diametric plane and having a partially cylindrical wall extending well beyond said diametric plane and having arcuate holding members on the outer 5 surface of said wall extending substantially from one edge to the other, and arcuate embossed strips on the holding members.
5. In a printing device, the combination of a segment having parallel arcuate ribs 10 thereon, embossed printing strips mounted on said ribs, and a terminal bar carried by the segment and extending across the ends of successive ribs to form a stop for the strips.
15. 6. In a printing device, the combination of a rigid segment having a partially cylindrical wall, parallel arcuate ribs thereon integral with the segment and continuously connected therewith at their bases, and embossed strips lying on said ribs and forming a printing surface, the ribs at one end being cut away to enable the ready insertions of the embossed strips.
20. 7. In a printing device, the combination of a printing member having arcuate strip holding means, embossed strips in arcuate form mounted thereon, and a positioning strip extending transversely of the embossed strips and having inturned ends occupying the channels between the holding means.
25. 8. In a printing machine, the combination of a member having parallel ribs with inwardly converging sides, embossed printing strips mounted on the ribs and having downwardly converging edge flanges engaging said sides, and a transverse positioning strip extending across the ends of a plurality of embossing strips and having inturned ends 30 occupying channels between some of said ribs.
35. 9. In a printing machine, the combination of a segment having parallel ribs with their sides converging leaving between them open channels with flaring sides, arcuate embossed
- printing strips having inwardly flanged edges underhanging the converging sides of the ribs, and transverse holding strips lying on the faces of several ribs and having in-turned end portions occupying corresponding channels and held in place by engagement with the inclined under surfaces of the ribs.
40. 10. A member having parallel ribs with underhanging edges, embossed strips on said ribs, having edge flanges underhanging the edges of the ribs, and a positioning strip having a flat portion of less height than the printing characters and of the a length corresponding to the width of a plurality of 45 ribs plus the intervening spaces and having inwardly turned end portions, whereby the strip may position a plurality of embossed strips.
45. 11. In a printing device, the combination of a member having parallel ribs with converging side walls, embossed printing strips mounted on the ribs and having converging edge flanges coating with the side walls and a transverse positioned strip having inwardly turned ends to engage opposite faces of 50 two of the ribs, one of said ends having its extremity curved outwardly to facilitate placing the strip.
55. 12. In a printing device, in combination, a segment having parallel arcuate ribs with underhanging side walls, arcuate embossed strips mounted on said ribs and having edge flanges engaging the underhanging side walls, a flat transverse strip of less height 60 than the embossed characters and of a length equivalent to the width of the faces of several ribs plus the width of the channels between such faces, said strips having inwardly turned ends engaging opposite edges of 65 two ribs.

In testimony whereof, I hereunto affix my signature.

CLIFTON CHISHOLM.
